(57) **CLAIM**

The ornamental design for a bag for multiple pairs of shoes, as shown and described.

DESCRIPTION

FIG. 1 is a left upper perspective view of the invention in an open position, the right upper perspective view being a mirror image thereof. Shoes in the open front and back sections are visible behind see-through covers, but are shown in dashed lines because they do not form part of the claimed design.

FIG. 2 is a left lower perspective view of the invention in an open position, the right lower perspective view being a mirror image thereof; and,

FIG. 3 is a left upper perspective view of the invention in a closed position, the right upper perspective view being a mirror image thereof.
